BUTTON SEWING ATTACHMENT

Vincent J. Muszynski, Buffalo, N. Y.

Application May 5, 1939, Serial No. 271,919

6 Claims. (Cl. 112—115)

This invention relates to an improved attachment for sewing machines and more particularly to an attachment for sewing buttons and the like to cloth.

It has been proposed in the past to provide special attachments for conventional sewing machines whereby the sewing on of buttons may be accomplished more or less automatically. Such attachments have, in the past, generally contemplated and provided for the sewing on of flat buttons wherein several thread openings extended through the button. In my present invention I provide a simple attachment whereby shank buttons may be sewed on with machines of the same type by merely substituting the attachment of the present invention for the attachments which are presently provided for sewing on buttons of the more common type.

In the following description and in the drawing, for the purpose of setting forth in detail a specific embodiment of the principles of my invention, I shall have reference to a standard Singer sewing machine of the general type shown in the patent to Sullivan No. 777,564 dated December 13, 1904. It is to be understood, however, that reference to a particular sewing machine and to specific details of construction of one form of my improved attachment is for purposes of exemplification only and my invention is not to be considered as limited thereby or in any other way, save as defined in the appended claims.

Such machines and mechanisms as have been heretofore proposed for the purpose of applying shank buttons have either been unduly complicated or have necessitated the utilization of a wholly special and unique sewing machine. In other instances the objection has been that individual buttons were not adequately located or held in proper position during the sewing on operation. The present invention aims to provide a simple attachment which adapts itself readily to standard sewing machines which are now conveniently available and in which ample provision is made both for original location of buttons with respect to the sewing mechanism and for firmly retaining buttons in located position until completion of the sewing on operation. A further merit of the attachment of my invention is its flexibility as regards the accommodation of buttons varying widely in size and shape. Other advantages will appear from a consideration of the accompanying drawing and ensuing description.

In the drawing:

Fig. 1 is a top plan view of my improved sewing machine attachment;

Fig. 2 is an elevational view thereof with portions of the head of a sewing machine indicated in dot and dash lines;

Fig. 3 is a fragmentary elevational view similar to Fig. 2 but taken from the opposite side of the attachment; and

Fig. 4 is a vertical cross sectional view taken approximately on the line IV—IV of Fig. 1.

In the drawing like characters of reference denote like parts and the numeral 10 designates a pivot block which is adapted to be positioned on the table of the sewing machine. A screw 11 serves to pivotally position the block 10 on the table of the machine and performs certain other functions the nature of which will presently appear. A bar 12 is fixed to the under side of the block 10 by the passage therethrough of the screw 11 and by virtue of a locating pin or dowel 13 which passes through the pivot block 10 and the bar 12.

The bar 12 is notched on its under side at a point spaced from the pivot block 10 and such notch is adapted to engage over a plate 15 which is provided upon the table of standard Singer sewing machines of the type mentioned above. The plate 15 is connected with suitable mechanism provided beneath the table of the machine and is thereby adapted to be reciprocated in timed relation with the operation of the stitching head of the machine.

As viewed in Fig. 1 the reciprocation of the plate 15 is in the direction from top to bottom of the sheet of drawing, or, as seen in Fig. 2, is a direction toward and away from the observer. These reciprocations are translated into pivotal oscillation of the bar 12 and the pivot block 10 in a horizontal plane and about the screw 11 by virtue of a connection between the bar 12 and the plate 15. This connection may simply be in the form of a screw (not shown) which passes through the bar 12 and the plate 15 and is conventional construction in machines of the type referred to above.

To the outer end of the bar 12 there is secured a plate 18 having an offset securing portion 19. The portion 19 may be secured directly against the end portion of the bar 12 as by a screw 20 and in the illustrated embodiment a number 50 of locating dowel pins 21 are provided. The plate 18 is provided for the purpose of supporting and positioning suitable button clamping means and means for controlling the button clamping and unclamping movements of such means and to this

end there is provided a relatively stationary clamping element in the form of a block 24 which is secured directly to the plate 18 as by means of screws 25. One edge of the block 24 is notched as at 26 and such notch is adapted to receive the shank 27 of a button 28 as is best shown in Fig. 1. The notch 26 is also adapted to permit downward passage of the needle both through the opening in the button shank and adjacent the end of the shank in alternate stitches. To this end an opening in the plate 18, approximately coincident with the notch 26, is also provided.

A pair of parallel rabbeted guide rails 29 and 30 are secured to the plate 18 and a slidable clamping plate 31 is disposed therebetween and partially thereunder and is guided thereby for movement toward and away from the stationary clamping block 24. The edge of the clamping plate 31 which is toward the block 24 is provided with an upturned flange 32 which, in use, engages against the front or outer face of the button 28 when the device is in clamping position.

The movable clamping plate 31 is normally spring-urged to a clamping position and the means for controlling clamping and unclamping movements thereof operate automatically or semi-automatically in a manner and by mechanism which will now be described. A control lever 35 is pivotally secured at one end adjacent the clamping plate 31 and such pivotal securing may be effected by providing an intermediate plate 36 adjustably fixed with respect to the one of the guide rails 29 by a screw and slot connection 37, the intermediate plate 36 pivotally supporting the lever 35 as by means of the bolt and nut connection 38.

An intermediate portion of the lever 35 connects with the clamping plate 31 by means of a longitudinal slot 39 formed in the lever and a cooperating screw 40 which is threaded into the clamping plate 31, see Fig. 4. So that buttons of various sizes may be accommodated, several spaced threaded openings 41 are provided in the plate 31 for alternatively receiving the lever connecting screw 40. The outer end of the lever 35 is pivotally engaged by one end of a link 42 which forms part of a toggle linkage, the other link 43 of which has its outer end pivotally attached to a rigid portion of the attachment, as for instance the guide rail 30. The adjacent ends of the links 42 and 43 of the toggle linkage are pivotally connected to each other and to an operating link 44.

When the operating link 44 is moved from right to left as viewed in Figs. 1 and 2 the toggle 42, 43 is spread and the lever 35 is pivoted counterclockwise around its pivotal mounting as viewed in Fig. 1 and the movable clamping element is moved away from the stationary clamp block 24. It will be seen that this movement is resiliently resisted by a coil spring 47, one end of which is anchored to the fixed pivot of the toggle link 43 while the other end is connected to the outer end of the other toggle link 42. The manner in which the operating link 44 is moved to effect unclamping movements will presently appear.

What may be termed a lifter bar is indicated at 50 and the right hand end of this bar, as seen in Figs. 1 and 2, extends downwardly and is received in a groove formed in a block 51 which is secured to the bar 12 as by a screw 52. The bar 50 is so arranged in the groove in the block 51 as to have pivotal movement about the groove 75 in a vertical plane and a leaf spring 54, which

is secured under the head of the pivot screw 11, has a notched outer terminal portion which engages about an upwardly projecting stud 55 which is rigidly associated with the bar 50, by reason of which the leaf spring 54 accompanies the bar 50 in its pivotal movements about the screw 11, and the leaf spring urges the bar 50 downwardly about its pivotal mounting in the grooved block 51.

By reason of the foregoing construction the entire assembly comprising the blocks 10 and 51 10 and the bars 12 and 50, together with the leaf spring 54 and the plate 18 carried by the bar 12, is oscillated about the pivot screw 11 in response to reciprocations of the plate 15, which in turn is actuated by conventional mechanism 15 provided beneath the table of machines of the class under consideration.

Toward the forward or free end of the bar 50 a hook 57 is rigidly associated with its upper side and the hook 57 is adapted to cooperate with a vertically reciprocating rod or bar 58 which forms a conventional part of machines of the class for which the attachment of the present invention is primarily intended. The bar or rod 58 terminates downwardly in a hook engaging 25 part 59 and is conventionally associated with the head 60 of sewing machines of this class.

The outer terminal portion of the bar 50 is notched as indicated at 64 in Fig. 1 and in such manner that when the bar overlies a button held in the clamping means, as illustrated in the drawing, space is provided for the downward passage of a sewing needle 65 which is carried by a conventional needle bar 66. By the arrangement shown and described the button is forcibly 35 prevented from pulling out of the clamping means upon upward or return movement of the needle and is in effect stripped therefrom by the terminal portion of the bar 50 which overlies the button. 40

At the conclusion of the actual sewing of the button to cloth in the intended manner, the bar 50 is given an upward movement, either automatically upon termination of the sewing-on operation or, as is at present more usual, by manipulation of a foot treadle by the operator. The upward movement of the bar 50, about its pivotal mounting in the groove in the block 51, lifts the outer end of the bar away from its position above the button and also positively releases the clamping mechanism so that the button may be lifted from its position in the attachment by merely moving the cloth to which it has been sewed to a new position or away from the machine.

The manner in which upward movements of 55 the bar 50 effect unclamping movements of the clamping means will now be described. Referring to Fig. 3, the plate 18 is provided with an upstanding flange 70 which serves as a pivotal support for a bell crank having a pair of arms 60 71 and 72. The outer end of the arm 71 has pivotally connected thereto a link 74 which may be in the form of a strap which pivotally engages one end of the link 44, the other end of which has been described as having pivotal connection 65 with the central joint of the toggle 42, 43.

The other arm 72 of the bell crank is disposed for engagement with an element which is rigidly but adjustably associated with the bar 50 in such manner that upward pivotal movement of the 70 bar 50 produces counterclockwise pivotal movement of the bell crank 71, 72 as viewed in Fig. 3 or clockwise movement as viewed in Fig. 2 and consequent movement of the links 74 and 44 toward the clamping elements. Movement of the 75

links 74 and 44 in this direction will, it is clear, result in spreading movement of the toggle links 42, 43 and result in opening movement of the movable clamping element 31 through the medium of the lever 35 and against the resistance of the coil spring 47.

The bell crank engaging means associated with the bar 50 comprises a pivot-bearing flange 80 having a base portion 81, the base portion 81 being secured to the bar 50, preferably by means of screws 82 which threadedly engage the bar 50 through a longitudinal slot 83 formed in the base portion 81 of the pivot-bearing flange 80. An arm 85 is secured to the bearing flange 80 by means of a screw 86 and it is to be understood that the position of the arm 85 is normally fixed with respect to the bar 50, pivotal movement of the former being resorted to only for the purpose of adjustment. The outer end of the arm 85 has associated therewith a headed stud 87 which engages the under side of the arm 72 of the bell crank lever during upward movement of the bar 50 to effect rotation of the bell crank against the resilient resistance of the coil spring 47.

It is believed that the operation of the attachment of the present invention will be clear from the foregoing. The relative positions of the several parts as they are illustrated in the accompanying drawing are the positions they occupy during the operation of sewing on a button. At the completion of the sewing on operation the operator will usually be required to manipulate a treadle or other manual control device for lifting the bar 50 about its pivot in the groove of the block 51, through the medium of the lifting bar 53 and against the resistance of the spring 47. As has been set forth in detail, such lifting movement effects a button-releasing or unclamping movement in two ways. First, the terminal portion of the bar 50 is lifted from its position overlying the button, in which position it serves in the nature of a vertical clamping member; and second, the horizontally movable clamping member 31 is moved away from the button whereby the button may be moved from the sewing-on position without resistance.

The foregoing attachment is simple and practical to use and may be employed with standard machines without alteration or interference with the usual construction of the sewing machine proper. By its use buttons throughout a fairly wide range of sizes may be placed in the sewing position and securely held with a minimum of effort and inconvenience and, consequently, with maximum rapidity and productive efficiency.

I claim:

1. An attachment for button sewing machines of the class described comprising a horizontally pivotal arm adapted to be engaged by a moving part of the machine for being alternately oscillated between successive stitches, button retaining means including a plate portion secured to the outer end of said arm for oscillation therewith and in vertical alignment with the stitching mechanism of the machine, an opening therethrough for the passage of a sewing machine needle, a stationary clamping element disposed at one side of said opening and a clamping element at the opposite side of said opening and movable upon said plate portion toward and away from the stationary clamping element, resilient means urging said movable clamping element toward the stationary clamping element, and toggle linkage

and an actuating element associated with the sewing machine proper for moving said movable clamping element away from the stationary clamping element against the resistance of said spring at the conclusion of a button sewing operation.

2. In a button sewing machine, the combination with stitch forming mechanism including a reciprocating needle, of a work support comprising a flat plate portion having disposed thereon a stationary clamp portion having an edge thereof notched to accommodate the shank portion of a shank button and a cooperating clamp portion movable toward and away from said stationary clamp portion, a vertical clamping element adapted in operative position to overlie a button disposed between said first two clamp portions and movable to unclamping position, and means engaging between said vertical clamping element and said movable clamp portion for moving said movable clamp portion away from said stationary clamp portion at the conclusion of a button sewing operation concurrently with the moving of said vertical clamping element to unclamping position.

3. An attachment for sewing machines of the class described for positioning and holding shank buttons during sewing-on operations, said attachment comprising a movably mounted element attachable to a reciprocating part of a sewing machine for being reciprocated thereby between successive stitches, horizontally directed clamping means supported by said movable element and including an element movable between button clamping and non-clamping positions, said movable clamping element having means associating it with a portion of said sewing machine which is adapted to be manipulated between button sewing operations for successively effecting button unclamping and clamping movements, resilient means urging said movable clamping element to clamping position, and horizontally extending toggle linkage acting between an actuating element of the sewing machine and the movable element of said clamping means for effecting unclamping movement at the conclusion of a button sewing operation.

4. In a button sewing machine, the combination with stitch forming mechanism including a reciprocating needle, of a vertically moving clamp bar adapted to overlie a button when in clamping position, and a work support comprising a flat plate portion having horizontally separable clamping elements disposed thereon, operating mechanism for said horizontally separable clamping elements comprising a toggle joint having one end anchored to said work support and the opposite end attached to one of said horizontal separable clamping elements, and means engaging between said vertically moving clamp bar and the medial pivot of said toggle joint for effecting separation of said horizontal clamping elements concurrently with upward unclamping movement of said vertically moving clamp bar.

5. An attachment for a button sewing machine having a reciprocable needle, a head for supporting the same, and a manually operable vertically movable bar likewise supported by said head; said attachment having a work support comprising a flat plate portion having disposed thereon a stationary clamp element and a horizontally movable clamping element for cooperation therewith, and means engaging between said manually operable bar and said horizontally movable clamping element for effecting horizontal un-

clamping movement of said clamping element upon manipulation of said manually operable bar.

5. An attachment for a button sewing machine having a reciprocable needle, a head for supporting the same, and a manually operable vertically movable bar likewise supported by said head; said attachment having a work support comprising a flat plate portion having disposed thereon a stationary clamping element and a horizontally
10 movable clamping element for cooperation therewith, a vertically movable clamping element

adapted in operative position to overlie a button disposed between said stationary and horizontally movable clamping elements, said horizontally and vertically movable clamping elements being connected for conjoint movement, and means engageable between said manually operable bar and one of said movable clamping elements for effecting unclamping movements of both movable clamping elements upon manipulation of said manually operable bar. 5
